DISPLAY CONTAINER

John V. Herr, Hastings on Hudson, N. Y., assignor
to Einson-Freeman Co., Inc., Long Island City,
N. Y., a corporation of Delaware

Application December 19, 1940, Serial No. 370,741

5 Claims. (Cl. 206—44)

My present invention relates generally to receptacles, and has particular reference to a display container.

The type of device to which my invention is primarily directed is of the cardboard variety, adapted to accommodate articles of merchandise that are packed into it by the manufacturer. When the container is received by the retailer, it is intended to be placed upon a counter in an opened condition, thereby making the merchandise available to prospective purchasers.

In receptacles of this general character, it is desirable that a display panel be provided for, so as to enliven the appearance of the box when the merchandise is exposed for sale, and to advertise or otherwise draw attention to the merchandise.

One of the objects of the present invention is to provide a means whereby a hinged lid, when lifted into an upright position, thereby exposing and displaying the contents of the box, will automatically be retained in its elevated position. This desirable result is achieved, by means of the present improved design, without calling upon the user of the box to do anything more than to lift the hinged lid from a normal closed position to an upright open position. The underside of the lid serves as a display surface which has been previously embellished or printed, and the simple act of lifting the hinged lid serves to place the container into immediate readiness for use on the counter.

Another object is to provide a means whereby the upward movement of the lid is automatically limited to an extent which arranges the lid in a predetermined proper display position.

It is a feature of my invention to control the cover by a simple frictional expedient which requires no extraneous parts and entails no manufacturing complications, relying solely upon the inherent capabilities and characteristics of the cardboard of which the container is made.

A further object of the invention is to provide for the foregoing advantages and capabilities in a manner whereby they may be incorporated in a container or box of the so-called "knock-down" variety. In such a device, the entire structure is adapted to be formed of flat sheet material, such as cardboard, cut and shaped to allow the parts to be readily set up into operative relationships. In one of the preferred embodiments of the invention, the container is composed of two blanks of cardboard; in another it is formed in its entirety of only a single piece.

I achieve the foregoing objects, and such other

objects as may hereinafter appear or be pointed out, in the manner illustratively exemplified in the accompanying drawings, in which:

Figure 1 is a perspective view of a container constructed in accordance with the present invention and shown in closed condition;

Figure 2 is a similar view, showing the lid or cover thrown back into open position;

Figure 3 is a view similar to Figure 2 showing the device as it appears from the rear;

Figure 4 is an enlarged fragmentary cross-sectional view taken substantially along the line 4—4 of Figure 1;

Figure 5 is an enlarged fragmentary cross-sectional view taken substantially along the line 5—5 of Figure 2;

Figure 6 is a fragmentary cross-sectional view substantially along the line 6—6 of Figure 5;

Figure 7 is a plan view of one of the blanks entering into the construction of the device illustrated;

Figure 8 is a plan view of another blank entering into the construction;

Figure 9 is a fragmentary cross-sectional view through a slightly modified construction;

Figure 10 is a perspective view of another embodiment of the present invention;

Figure 11 is a cross-sectional view, taken substantially along the line 11—11 of Figure 10;

Figure 12 is a similar cross-sectional view, showing the box in closed condition;

Figure 13 is a cross-sectional view taken substantially along the line 13—13 of Figure 11; and

Figure 14 is a plan view of the blank entering into the construction of Figures 10—13.

The boxes I have chosen to illustrate are substantially square and shallow; although it will be understood that wide variations in size and proportions are feasible, depending upon the nature of the merchandise intended to be accommodated within the box.

In all of the present drawings, I have shown the container in an empty condition, but it will be understood that, in actual practice, the container will be filled with merchandise that can be shipped and stored while the box is closed, and displayed when the lid is thrown back.

The structural nature of the container illustrated in Figures 1—9, can best be described in connection with Figures 7 and 8.

A single blank of suitable sheet material, such as cardboard, is cut and shaped to define the various panels and sections shown most clearly in Figure 7. Hinged at 24 to the panel 20, ultimately constituting the bottom wall, are the suc-

cessively hinged panels 25, 26, and 27. The panels 25 and 26 are ultimately intended to be doubled upon themselves along the line 28 to form the front wall of the box. The panel 27 is an extension intended ultimately to lie over the bottom wall 29.

At its opposite ends, the panel 25 is provided with the flaps 29 and 30, the hinge lines 31 and 32 serving ultimately to define the front vertical edges of the container.

Hinged to the bottom wall 29, along the line 33, are the successively hinged panels 34, 35, and 36. The panels 34 and 35 are ultimately to be doubled upon themselves along the hinge line 37 to define a two-ply side wall of the container. The panel 36 is ultimately intended to lie flat upon the bottom wall 20. Attached to the front end of the panel 35 is the flap 38. The hinge line 39 ultimately lies alongside of the hinge line 31.

Hinged to the bottom wall 20, along the opposite line 40, are the panels 41, 42, and 43, and the flap 44, which correspond to the elements 34, 35, 36, and 38, respectively.

The rear wall of the box is defined by the panel 23 which is hinged to the bottom wall 20 along the line 46. At each end, the panel 23 is provided with the hinged tabs 47. The hinge lines 48 define the rear vertical edges of the box when the structure is set up and the lid is in closed position.

For a purpose presently to be explained, each of the tabs 47 is substantially trapezoidal in shape, i. e., the upper edge 49 converges toward the opposite edge.

Referring now to Figure 8, it will be observed that the panel 50, intended to serve as the lid of the container, is hinged along the line 51 to the element 52, and the latter portion has rectangular end flaps 53 and a hinged extension 54.

The element of Figure 8 is associated with the element of Figure 7 by means of the connecting panel 21. This panel is hinged, as at 22, to the upper edge of the rear wall 23, and is provided with the hinged extension 21' adapted to engage with the outer surface of the lid 50. This engagement may be accomplished in various ways, and I have illustratively shown the possibility of applying an adhesive to the extension 21', whereby this extension may be adhesively secured to the midportion of the lid 50.

Under certain circumstances, the connecting panel 21 might be made coextensive in area with the lid 50, and in such an event, the panel 21 might be formed, if desired, of one piece with the lid 50, being hinged to it along the free edges of the elements 21 and 50.

In either case, the portion 52 of the cardboard element shown in Figure 8 will be arranged in front of the rear wall 23, so that the hinge line 51 lies in substantial registry with the hinge line 22 while the hinge line 55 lies in substantial registry with the hinge line 46. The width of the element 52, however, is very slightly smaller than the width of the rear wall 23, so that the connecting panel 21 is normally in contact with the lid 50 when the container is in closed position as shown in Figures 1 and 4.

In setting up the box, the rear wall 23 is first folded upwards along the line 46. This necessitates that the blank of Figure 8 be folded along the line 55, thereby laying the extension 54 along the rear portion of the bottom wall 20. The flaps 53 and the tabs 47 are then bent forwardly along the hinge lines 48 and 56.

The next step is to swing the panel 25 upwards

and to swing the flaps 29 and 30 into rearward directions.

The side walls of the container are then set up. This involves first folding the panels 34 and 41 upwards, and then folding the panels 35 and 42 downwards into the box, thereby bringing the extensions 36 and 43 into positions lying flatwise over the bottom wall 20. During this procedure, the flaps 53 and the tabs 47, and the flaps 29 and 30, are engaged in sandwiched relationship between the two plies of the side walls. Also, the flaps 38 and 44 are brought into positions parallel to and directly behind the front panel 25.

The final step is to fold the panel 26 into the box, thereby catching the flaps 39 and 44 and disposing the extension 21 along the bottom wall of the box.

With the box thus set up, it is ready to be filled with articles of merchandise, and, when filled, the cover is swung downwardly into the position of Figure 1. The filled container is then ready for storage or shipment.

When it is ready for use as a display container, the box is placed on the counter, and the lid is swung into the display position of Figures 2 and 3.

Because of the nature of the present construction, and the association of parts hereinbefore described, the cover of the container is automatically caused to be held in its lifted position. The way this is accomplished is shown most clearly in Figures 2-6.

The rear wall 23, by virtue of its hinged connection to the rear edge of the bottom wall 20, is mounted for swinging movement about a hinge axis coincident with the lower rear edge of the box. By means of the present construction, the lid 50 is anchored to the side walls of the box so as to allow a swinging movement about a hinge axis (the line 51) which is parallel to and elevated above said rear lower edge. This anchorage results from the fact that the flaps 53 are engaged by the side walls of the container, and are connected to each other by the element 52 to which the lid 50 is hinged.

The connecting panel 21 serves as a means for interconnecting the rear wall 23 and the lid 50 in a manner whereby lifting of the lid 50 serves automatically to swing the rear wall 23 in a rearward direction. More particularly, it will be observed that the engagement of the connecting panel 21 with the lid 50 serves to lock these parts

against relative sliding movement. It makes no difference, in this regard, whether the panel 21 is smaller than the lid 50, as shown in the present drawings, or whether it is of equal size; and it makes no difference whether the panel 21 is adhesively secured to the lid 50, as in the present case, or whether it is formed in one piece with the lid or otherwise attached to it. As a result of the impossibility of relative sliding movement, the act of lifting the lid from the position of Figure 4 to the position of Figure 5 brings about a rearward movement of the rear wall 23, this wall swinging about the line 46 as a hinge axis.

The present invention takes advantage of this rearward movement, and provides a means that can be controlled by this movement for limiting the swing of the lid and also retaining the lid in lifted position.

A preferred way of accomplishing this lies in the provision of the tabs 47 hereinbefore described. One tab would serve the purpose, but for the sake of symmetry and balance, two are preferable. One of these tabs is snugly accommodated between the plies 34 and 35 of one of

the side walls. These plies are joined together along the top edge 31, and define a rearwardly-opening friction pocket within which the tab 47 is slideable. When the wall 23 moves rearwardly into the position shown in Figures 2, 3, and 5, the tab 47 is swung arcuately upwards into the relatively confined region of this friction pocket, i. e., the region directly beneath the top edge of the side wall. This region of the friction pocket exerts a sort of pinching action upon the tab 47 as the upper edge portion of the tab is forced into the position of Figure 6.

The same is true with respect to the other tab 47, adapted to slide in a frictional manner within the pocket defined by the plies 41 and 42 of the other side wall of the box.

The upper end of each friction pocket serves as an abutment, arranged in the path of movement of the upper edge of the corresponding tab, whereby the upward swinging movement of the lid is limited to a predetermined extent.

The upper edge 49 of the tab 47 is preferably convexly shaped so that at least a portion of it lies in the confined region of the friction pocket at all times. In laying out the contour of the edge 49, the curvature of the portion nearest the hinge line 48 has its center at the junction between the lines 48 and 46, and the tangential straight portion of the edge 49 is laid out at an angle which is determined by the rearmost position to which the display panel 50 is to be pushed when the box is used.

It is quite feasible, however, though not as efficient, to lay out the upper edge of the tab 47 along a straight line. This is shown in Figure 9, in which the upper edge 49' of the tab 47' is devoid of any curvature.

Obviously, the container may be closed, when desired, by merely swinging the cover downwards again; and one of the advantages of the invention lies in the fact that the box can be opened and closed any number of times, as conditions may require, and that the cover will automatically remain up whenever it is raised to open position.

In Figures 10-14, I have illustrated a modified structure in which the lid is anchored in a different manner, in which the frictional engagement of the tabs is of a different character, and in which the entire structure can be formed of a single blank of cardboard or the like.

Referring first to Figure 14, it will be observed that the bottom wall 60 is hinged along its rear edge 61, to the rear wall 62. Hinged to the upper edge 63 of the rear wall is the connecting panel 64 which carries the extension 65. The trapezoidal tabs 66 are hinged, as at 67, to the ends of the rear wall 62. The upper edge of each tab 66 has a convexed portion 68 lying adjacent to the hinge line 67, and a relatively straight portion 69. There is a step or shoulder between each curved portion 68 and the adjacent straight portion 69.

To the forward edge 70 of the bottom wall is hinged the front wall 71. At its ends, this wall is provided with the hinged flaps 72.

Hinged to the upper edge 73 of the front wall is a panel of frame-like character comprising the end strips 74 and 75, and the lateral portions 76. Hinged to these lateral portions are the side walls 77, and each of these walls is, in turn, provided with a hinged flap 78.

Hinged to the strip 75, along the line 79, is the lid 80.

After this blank has been formed, it is folded

upon itself to bring the hinge line 79 into substantial registry with the hinge line 63, and an engagement is then effected between the connecting panel 64 and the lid 80. This may be accomplished in any suitable manner, but I prefer to apply adhesive to the extension 65, and to secure this extension to the midportion of the lid 80, as shown most clearly in Figures 10 and 11.

The assembly of the box is completed in a very simple manner, by merely folding the tabs 66 along the lines 67 to bring them into substantially parallel planes, by similarly folding the flaps 72 into substantially parallel planes, and finally tucking the flaps 78 into the positions shown in Figure 13.

The parts are so designed that the connecting panel 64 lies over and in contact with the lid 80 when the box is in the closed position shown in Figure 12.

It will be observed that the rear wall 62, as in the previous construction, is mounted for swinging movement about the hinge axis 61, which is coincident with the lower rear edge of the container. Also, the lid 80 is anchored to the side walls of the container so as to allow a swinging movement about the hinge axis 79, which is parallel to and elevated above said rear lower edge. The anchorage of the lid is in this case accomplished by means of the strip 75 which extends across the box and connects the side walls 77, the lid 80 being hinged to this strip.

When the box is to be opened, for the display of its contents on a counter or the like, the lid 80 is swung upwardly into the position shown in Figures 10, 11, and 13. For the reasons hereinbefore described, this swinging movement of the lid automatically brings about a rearward swinging of the rear wall 62. This, in turn, swings the trapezoidal tabs 66 arcuately upwards. During this movement, the upper edge portion 68 of each tab presses frictionally against the undersurface of the strip 75. While this frictional engagement is sufficient to retain the lid in any partially opened position, it is contemplated that the lid will be swung back far enough to bring the straight portion 69 of each tab against the underside of the strip 75 and of the overhang 76. When this limiting position is reached, the curved rear portion of each tab will have snapped into the position of Figure 11, thereby locking the lid against return movement.

It will be understood that one of the tabs 66 would be sufficient for the present purpose, but that the provision of two tabs contributes to a desirable symmetry and to balanced operation.

In general, it will be understood that those skilled in the art may make changes in the details herein described and illustrated without departing from the spirit and scope of the invention as expressed in the appended claims. It is, therefore, intended that these details be interpreted as illustrative, and not in a limiting sense.

Having thus described my invention and illustrated its use, what I claim as new and desire to secure by Letters Patent is:

1. In a cardboard display container, a bottom wall, side walls, a rear wall hinged to the rear edge of the bottom wall, a lid, means anchoring the lid to said side walls to allow swinging movement about a hinge axis parallel to and above the lower rear edge of the container, means interconnecting said lid and rear wall for swinging the rear wall rearwardly when the lid is lifted, and means controlled by said rear wall for retaining said lid in lifted position, said anchoring

means comprising a strip extending across the container and connecting the upper edges of said side walls, said lid being hinged to said strip.

2. In a cardboard display container, a bottom wall, side walls, a rear wall hinged to the rear edge of the bottom wall, a lid, means anchoring the lid to said side walls to allow swinging movement about a hinge axis parallel to and above the lower rear edge of the container, means interconnecting said lid and rear wall for swinging the rear wall rearwardly when the lid is lifted, and means controlled by said rear wall for retaining said lid in lifted position, said anchoring means comprising flaps engaging the side walls, and an element lying in front of the rear wall and connecting said flaps, said lid being hinged to said element.

3. In a cardboard display container, side walls, a rear wall mounted for swinging movement about a hinge axis coincident with the lower rear edge of the container, a strip extending across the container and connecting the upper edges of said side walls, a lid hinged to said strip for swinging movement about a hinge axis parallel to and above said lower rear edge, means interconnecting said lid and rear wall for swinging the rear wall rearwardly when the lid is lifted, and means controlled by said rear wall for retaining said lid in lifted position, said last-named means comprising a tab projecting forwardly 30

from one end of the rear wall and having a convexed upper edge adapted to engage frictionally with the underside of said strip.

4. In a cardboard display container, side walls, a rear wall mounted for swinging movement about a hinge axis coincident with the lower rear edge of the container, a strip extending across the container and connecting the upper edges of said side walls, a lid hinged to said strip for swinging movement about a hinge axis parallel to and above said lower rear edge, means interconnecting said lid and rear wall for swinging the rear wall rearwardly when the lid is lifted, and means controlled by said rear wall for limiting the upward swing of the lid and retaining it in lifted position, said last-named means comprising a tab projecting forwardly from one end of the rear wall and having a convexed upper edge portion adapted to engage frictionally with the underside of said strip, and an overhang provided on the adjacent side wall to serve as an abutment adapted to be encountered by another portion of the upper edge of said tab.

5. In a cardboard display container, the combination with the elements set forth in claim 3, of a bottom wall and a front wall, said bottom wall, front wall, rear wall, side walls, and lid being integral portions of a single blank of cardboard.

JOHN V. HORN
